INSULATED BOWL

Roger R. Sacia and Kenneth B. Welch, West Bend, Wis.,
assignors to Kenro Corporation, Fredonia, Wis., a corporation of Wisconsin

Application March 2, 1955, Serial No. 34,838

Term of patent 14 years

(Cl. D44—15)

Fig. 1

Fig. 3

Fig. 1 is a perspective view of an insulated bowl, showing our new design;

Fig. 2 is a transverse vertical sectional view thereof; and
Fig. 3 is a top plan view thereof on an enlarged scale.

We claim:

The ornamental design for an insulated bowl, substantially as shown.
